UNITED STATES PATENT OFFICE.

JAMES E. HANGER, OF WASHINGTON, DISTRICT OF COLUMBIA.

CHAIR.

No. 856,058.

Specification of Letters Patent.

Patented June 4, 1907.

Application filed February 16, 1906. Serial No. 301,379.

To all whom it may concern:

Be it known that I, JAMES E. HANGER, a citizen of the United States, residing at Washington, District of Columbia, have invented 5 certain new and useful Improvements in Chairs, of which the following is a specification.

This invention relates to improvements in chairs, and more particularly to the construction and arrangement of the back and seat portions.

The object of my invention is to provide a chair back constructed of a series of slats curved at or near their lower ends in such a 15 manner as to form a perfect support for the small of the back, and straight at their tops so as to properly support the shoulders, the said slats being connected to each other and to the frame of the chair by a transverse 20 spring or springs which allow the entire series as well as the individual slat to accommodate or adapt itself or themselves to the curvature or form of the back, and thus insure perfect 25 ease and comfort to the occupant.

Another object of my invention is to provide a chair seat so mounted upon the frame as to have a rocking or oscillating movement, which is controlled by a coiled spring so arranged as to allow the seat to tilt backward 30 sufficiently to adapt itself to the form of the occupant and distributing the pressure evenly, thus affording great ease and comfort.

With these ends in view and such others as may hereinafter appear, my invention consists in certain component and co-operative parts, and in the novel manner of combination and arrangement of said parts, all of 35 which will be more fully described and specifically pointed out in the appended claims.

In the drawings forming a part of this specification:—Figure 1, is a vertical sectional view of a chair illustrating my invention as applied; Fig. 2, is a front view of a 40 chair illustrating the back; Fig. 3, is a plan view illustrating the slats and transverse springs; Fig. 4, is a similar view illustrating a 45 modification; Fig. 5, is a similar view illustrating another modification, and Figs. 6 and 7 are perspective views of the clamps for retaining the slats to the springs.

Referring by numerals to the drawings, 1 represents the legs of the chair which extend up sufficiently above the seat to form a support for the arms 2. These legs are secured 50 together by horizontal braces 3, and transverse braces 4, and 5, the braces 3, support a

transverse rod 6, which is a little front of the center of the chair and provides a pivotal support for the seat 7, the forward end of which is normally held against the transverse 60 brace 4, by coiled springs 8, wound upon the rod 6, with one end extending forward and secured in the braces 3, while the other end extends in the opposite direction and engages the bottom of the seat which is limited in its 65 movement by the transverse brace 5, however, a sufficient movement is provided to allow the seat to adapt itself to the desired inclination to render ease and comfort to the occupant.

The frame for the back of the chair consists of parallel side sections 9 and transverse braces 10. This frame may be stationary or pivoted, as desired, and provided with a head-rest 11, or such head-rest may be eliminated. Mounted upon transverse springs 12, which are secured at each end to the respective side sections 9, are a series of slats 13, which are straight at their upper ends 14, and curved at or near the lower ends as 70 shown at 15, to fit the small of the back. These transverse springs which may be one or more, as desired, consists of a steel spring wire bent at regular intervals to form a 75 U-shaped loop slightly contracted at the neck, 80 to which is secured the slat 13, by means of clamps 16, and 17, which are so constructed as to allow a slight movement of the spring portion held therein.

On Fig. 4, I have shown a modification 90 of the transverse spring wherein the spring consists of two steel wires 18 and 19, bent in a zig-zag manner in reverse directions and secured to the slats by the clamps 16 and 17, so that each wire will be permanently secured to every other slat, and have a slight 95 movement in the clamp securing it to the intermediate slat, the permanent and loose clamps alternating throughout.

In Fig. 5 I have shown another modification 100 wherein the transverse wire is coiled as shown at 20, around a stud 21, upon the back of the slat. This form as in the case of the forms above described, may be used separately or in conjunction with others, 105 however, I have found that two of such springs give the best results.

Minor changes in the transverse spring, such as connecting the slats by intermediate spiral springs, and other details of construction, may be resorted to without sacrificing the advantages of my invention.

Having thus described the various features of my invention, what I claim as new and desire to secure by Letters Patent, is:—

1. In a chair back, the combination with the frame, a transverse spring, a plurality of independent slats secured to said spring, substantially as specified. 30
2. In a chair back, the combination with the frame, transverse springs secured upon the frame, a plurality of independent slats secured to the springs, substantially as specified. 35
3. In a chair back, the combination with the frame, a series of transverse springs secured to the sides of the frame, a plurality of independent slats clamped to the springs, substantially as specified. 40
4. In a chair back, the combination with the frame, a transverse spring connecting the sides of the frame, a plurality of independent slats secured upon the spring, the upper ends of the slats being straight and the lower ends curved, substantially as specified. 45
5. In a chair back, the combination with the frame, a series of transverse springs connecting the sides of the frame, a plurality of independent slats curved at their lower ends, means for securing the slats to the springs, substantially as specified. 50

6. In a chair back, the combination with the frame, two transverse springs composed of a series of loops connecting the sides of the frame, a plurality of independent slats curved at their lower ends, means for securing the slats to the loops, substantially as specified. 35

7. In a chair back, the combination with the frame, two transverse springs composed of a series of U-shaped loops the ends of which are secured to the sides of the frame, a plurality of independent slats being straight 40 throughout a portion of their length and the other portion curved, and means for securing the slats to the said loops, substantially as specified.

8. In a chair back, in combination with the frame, a plurality of transverse springs, the respective ends of the springs being secured to the sides of the frame, each spring being composed of a series of loops, a plurality of slats, each slat being straight throughout a 50 portion of its length, and curved throughout the remaining portion, and means for securing the slats to the loops, substantially as specified.
